UNITED STATES PATENT OFFICE.

GEORGE W. PERKINS, OF BOSTON, MASSACHUSETTS, ASSIGNOR TO HEATON PENINSULAR BUTTON FASTENER COMPANY, OF BOSTON, MASSACHUSETTS, A CORPORATION OF MAINE.

STAPLING TOOL.

Application filed January 17, 1922. Serial No. 529,909.

To all whom it may concern:

Be it known that I, GEORGE W. PERKINS, a citizen of the United States, residing at Boston, county of Suffolk, State of Massachusetts, have invention a certain new and useful Improvement in Stapling Tools, of which the following is a specification, reference being had therein to the accompanying drawings.

10 The invention relates to an improvement in stapling tools. It has special reference to a tool for fastening two objects together by means of metallic staples. It is especially intended for use in attaching buckles to 15 leather or other sheet material, although not limited to such use. The special object of the present invention is to form a small loop or eye in the head of the staple by shaping the eye over the cross-bar of the 20 buckle at the same time that the legs of the staple are driven through the leather or other sheet material and clinched.

25 The invention will be fully understood from the following description when taken in connection with the accompanying drawings and the novel features thereof will be pointed out and clearly defined in the claim at the close of this specification.

Fig. 1 is a side elevation of a hand tool 30 embodying the invention, showing the jaws open preparatory to the stapling operation.

Fig. 2 is a side elevation showing the jaws in the position after the staple has been driven home and clinched.

35 Fig. 3 is a section on line 3—3 of Figure 1.

Fig. 4 is a detail view of a staple such as is intended to be used with the tool.

40 Fig. 5 is an enlarged sectional view showing a buckle attached to a piece of sheet material with the staple by means of the tool embodying the invention.

45 Fig. 6 is a plan view of a buckle stapled to a strap by a tool embodying the invention.

Referring now to the drawings, the tool comprises two members A, B pivoted together at 1, the member A comprising a handle portion 2 and a jaw portion 3, and 50 the member B comprising a handle portion 4 and a jaw portion 5. The two members A, B are pivoted together something after the manner of a pair of pincers. The jaw portion 3 will be referred to for convenience 55 as the upper jaw and the jaw member 5 as

the lower jaw. The staple, such as intended to be used in the tool, is shown in Figure 4 and is designated by the numeral 6, said staple being of the ordinary shape of a staple with two legs and a connecting head. 60

The jaw 3 is formed with a vertical slot 7 at its forward end and secured within this slot, as by screws 8 or any other suitable means, is a block 9 which will be referred to as the staple driver and loop former. 65 Said block 9 is formed with two vertical holes 10—10 within which are loosely fitted the legs 11—11 of a U-shaped member H, which will be referred to as the staple holder. This staple holder is formed with 70 two longitudinal grooves 12—12, respectively, in the inner sides of the two legs thereof. The two legs 11—11 of the holder are spaced sufficiently far apart and the grooves 12—12 are of sufficient width and 75 depth so that the two legs of the staple will fit into the said two grooves. A staple may be inserted into the holder H from the lower end of the holder when the jaws are spread open, as in Figure 1, the head of the staple being uppermost so that the legs extend 80 downward. The staple should preferably be shoved up into the holder far enough so that the legs do not protrude below the lower end of the holder before the stapling operation is begun. 85

A spring 13 lies on the upper face of the upper jaw 3, being secured to the jaw near its rear end, as by a screw 14, the forward end being free and extending forward and resting upon the head of the staple holder H, as shown in Figures 1 and 2, to give an elastic downward pressure thereon. Preferably a guide pin 15 is employed which projects from the upper side of the jaw and 90 extends through a hole in the spring. 95

The lower end of the block 9 is formed with a groove 16 intermediate the two holes which form the guideway for the staple holder for the purpose of aiding in forming 100 the loop in the staple, as will be hereinafter described.

The lower jaw 5 has fixedly mounted within it near its outer end an anvil 17 which is provided with a shank 18 extending down into a socket of the jaw formed to receive it. The anvil may, however, be secured to the jaw in any other suitable way. This anvil has formed in its upper surface 105 two concave depressions 19—19 which are 110

adapted to cooperate with the driving member of the upper jaw to clinch the legs of the staple.

In Figure 6, there is shown a buckle of the type with which the device is especially intended to be used. Said buckle comprises a frame 20 of substantially rectangular contour with rounded corners and a middle crossbar 21 to which is pivotally connected a tongue 22.

In operation, the strap, or other piece of sheet material 23 to which the buckle is to be attached, will be laid upon the upper side of the anvil 17 and the buckle placed and held upon the upper side of the strap 23 in proper position for the crossbar 21 to lie upon the rib 24, which forms the ridge between the two depressions 19-19 in the anvil. The staple having previously been inserted into the holder H of the upper jaw, the two handles 2, 4 will be squeezed toward each other, thereby closing the two jaws. After the upper jaw has moved part-way down towards the lower jaw, the lower ends of the legs 11-11 of the staple holder will engage the upper face of the strap 23 clamping the strap against the anvil 17, the spring 13 holding the staple holder with a yielding pressure against the strap 23. As the jaws are further closed the lower end of the block 9 will bear against the head of the staple and force it downward, the legs of the staple straddling the crossbar 21 of the buckle, and by still further continuing the pressure the legs of the staple will be forced through the strap and the ends will be turned up and clinched by reason of the concave formation of the depressions 19-19 in the anvil.

The groove 16 in the lower end of the

block 9 will come down over the crossbar 21 of the buckle and the lower end portions 25-25 of the block 9 on opposite sides of the groove 16 will engage the head of the staple at opposite sides of the median line of the head, forcing the staple home while the middle portion of the head which rests upon the crossbar 21 will be bent over the crossbar forming a loop 26 which is received in the groove 16. The loop thus formed is shown in Figure 5.

What I claim is:

A hand stapling tool consisting of two jaw members pivotally connected together, one of said jaws being provided with an anvil which has two depressed portions with an intermediate rib for clinching the staple, the other of said jaws being provided with a cooperating staple driving member formed with two parallel apertures, a U-shaped staple holder having two parallel legs which pass loosely through the apertures in said driver, said legs having longitudinal grooves to hold a staple, said driving member being formed with a transverse groove in its lower end intermediate the legs of the staple holder, the portions of the driving member on the opposite sides of the transverse groove engaging the head of the staple to drive the legs of the staple through the material to which the article is to be attached when the jaws are brought together, and a spring which engages the staple holder and normally causes the lower end of the legs to project below the driver to clamp the said material to the anvil during the driving of the staple.

In testimony whereof I affix my signature.

GEORGE W. PERKINS.
